HOUSEHOLD STILL FOR DRINKING WATER AND THE LIKE

Dimitri Gregory Soussloff, Weston, Conn., assignor to
American Machine & Foundry Company, a corporation
of New Jersey

Filed Jan. 22, 1962, Ser. No. 68,395

Term of patent 14 years

(Cl. D16—2)

FIG. 1

FIG. 2

FIGURE 1 is a perspective view of a household still for drinking water and the like showing my new design;

FIG. 2 is a perspective view thereof, taken from the bottom and opposite side of FIG. 1.

The dominant features of my design reside in the portions shown in full lines. The cord member disclosed in FIG. 2 is broken away to indicate indeterminate length.

I claim:

The ornamental design for a household still for drinking water and the like, as shown and described.
